UNITED STATES PATENT OFFICE

HARRY H. FISHER, OF SYRACUSE, NEW YORK

SLICING MACHINE

Application filed April 16, 1926. Serial No. 102,384.

This invention relates to a slicing machine of the hand-operated rotary cutter type adapted to be clamped to a table or other available support for use in slicing potatoes, beets, cabbage, lettuce and other vegetables and involves an automatically operated follower for feeding the work to the rotary cutter.

The main object is to provide a simple and highly efficient device of this character which may be manufactured and sold at a comparatively low cost and used in households for the various kinds of work to which it is adapted.

15 One of the specific objects is to provide the device with a relatively broad work-supporting shelf having a guide flange at one side along which the work may be fed to the cutter.

20 Another object is to provide the automatic feeding means for the follower with a sectional nut capable of being released for quick return of said follower at the end of the slicing operations.

25 Other objects and uses relating to specific parts of the apparatus will be brought out in the following description.

In the drawings:—

Figure 1 is a top plan of a slicing machine 30 embodying various features of my invention.

Figures 2 and 3 are sectional views taken on lines 2—2, and 3—3, respectively, Figure 1.

35 Figure 4 is a detail sectional view through the cutter head showing the manner of fastening the cutter blades in operative position.

Figure 5 is a side elevation partly in section of a modified means for feeding the follower and work to the cutters.

As illustrated, this machine comprises a bracket clamp —1— having its lower end provided with a horizontal slot —2— for receiving a portion of a table or other support —a— shown by dotted lines in Figure 2, the upper wall as —3— of the slot being adapted to rest upon the upper surface of the support —a— while the lower wall or arm —4— of the slot is provided with a threaded aperture —5— for receiving a thumb screw —6—,

the latter being provided with a flat head —7— for engaging the underside of the table —a— and holding the machine in operative position on said support.

The bracket —1— is provided with arms 55 —8— and —9— projecting upwardly from the upper wall —3— of the slot —2— for receiving and supporting at their upper ends a horizontal work table —10— which extends forwardly some distance beyond the arm 60 —9— and is provided near its opposite ends with depending journal bearings —11— and —12— for receiving the opposite ends of a rotary screw shaft —13—.

The major portion of the shaft —13— between the bearings —11— and —12— is threaded at —14— and is adapted to be engaged by a sectional nut —15— which is pivoted at —16— to a sliding carriage —17— and is provided with a finger piece —18— by which it may be disengaged from the threaded portion —14— of the shaft to allow the carriage —17— to be returned by hand independently of the shaft, but is yieldingly held in engagement with the shaft by a coiled spring —18'—.

The carriage —17— is movable lengthwise of the shaft —13— in a lengthwise slot —19— in the work table —10— and is provided with a follower —20— extending above the upper face of the table —10— and provided on its front face with a series of spurs —21— for engaging the work and holding it against lateral slipping movement, said follower being also provided with a rearwardly projecting handle —22— by which the carriage supporting the same may be moved along the work table.

The rear end of the shaft —13— is provided with a hand crank —23— by which it may be rotated.

A circular cutter supporting disk —24— is secured to the front end of the shaft —13— and is provided with a series of, in this instance four, tangential slots —25— arranged in uniformly spaced relation about the axis of the shaft —13— substantially tangential to the periphery thereof for receiving a corresponding number of knife blades —26—.

These knife blades are secured by bolts 100

—27— to the outer faces of axially inclined ribs or bosses —28— on the front face of the disk —24— to support the knives —26— in planes at an angle to the plane of rotation of the disk —24— with their inner cutting edges extending through their corresponding slots —25— and beyond the inner face of the disk, leaving sufficient clearance between the cutting edges and adjacent walls of the slot to allow the sliced material to pass therethrough.

The slots —25— and knives —26— extend tangentially with reference to the periphery of the shaft —13—, the major portion of the distance between said shaft and the periphery of the disk —24— so that the knives may be used to cut vegetables of relatively large diameter.

The object in extending the knives —24— 20 tangential to the periphery of the shaft —13— is to cause them to cut the articles operated upon with a shearing motion.

The work-table —10— extends laterally some distance beyond opposite sides of the shaft —13— with its upper surface in a horizontal plane above said shaft, for supporting relatively large articles and is provided along its rear longitudinal edge with an upwardly and inwardly projecting guide flange 30 —30— against which the work is adapted to rest and to guide said work in its forward movement along the table toward the cutter.

A guard plate —31— is secured at one end to the flanged side of the table —10— 35 and extends across the periphery and front face of the cutter disk —24— in spaced relation to said disk for concentrating and deflecting the sliced material downwardly into an underlying receptacle, not shown.

40

Operation

When it is desired to use this device for cutting potatoes and other vegetables it may be clamped to a table or equivalent support 45 —a— in the manner described ready for use.

The carriage —17— and with the follower —20— thereon are withdrawn from the cutter —24— a sufficient distance to permit the work to be sliced to be placed upon the table 50 —10— between the cutter disk and follower with one side of the work resting against the guide flange —30—.

The shaft —13— may then be rotated by means of the hand crank —23— to cause the 55 follower to feed the work forwardly against the inner face of the cutter —24— while at the same time the cutter is being rotated by the shaft —13— to successfully move the cutting blades —26— into cutting engagement 60 with the work for slicing the same and allowing the slices to pass through the slots —25—.

The cutting edges of the blades —26— face in the direction of rotation of the disk —24— and cooperate with the front edge of 65 the guide flange —30— to cut the vegetables

or other articles into slices as the disk continues to rotate, the flange —30— serving to hold the work against lateral displacement by the cutters.

As the cutter disk is rotated more or less 70 rapidly the slices will be thrown rearwardly from the front face of the cutter with more or less force against the deflector plate —31— which serves to deflect the slices downwardly where they may be collected at the underside 75 of the cutter in any suitable receptacle, not shown.

When the slicing operation is completed the carriage may be returned by hand by simply releasing the nut section —15— from 80 engagement with the threaded shaft —13—.

In Figure 5 is shown a modified means for feeding the carriage —17— toward the cutter consisting of a coiled spring —14'— interposed between the bearing —11— and carriage —17— thereby avoiding the use of the threaded portion —14— and nut —15—.

In the use of this modification the follower —20— is drawn back by hand against the action of the spring —14'— and the article to be sliced is then placed between the follower and cutter which latter is rotated in the manner described, the spring —14'— serving to feed the follower —20— and work engaged thereby forwardly toward the cutter as the slicing operation continues.

The entire frame —1—, follower —20— and cutter disk —24— are preferably made of cast iron cut away as much as possible without sacrificing its strength to reduce its weight and cost of manufacture, the arm —9— being preferably Y-shaped so that its opposite arms may support the work table —10— at opposite sides of the shaft —13— as shown in Figure 3.

What I claim is:

A slicing machine of the character described comprising a work table having a central lengthwise opening therethrough and journal bearings at opposite ends of the openings, a screw shaft extending lengthwise of the opening beneath the work table and in vertical alignment with said opening, said shaft having its opposite ends cylindrical and journaled in said bearings and its intermediate portion provided with screw threads, a hand-crank on one end of the shaft, a clamping device depending from the end of the work table nearest the hand-crank for clamping the machine to a support, a rotary disk on the other end of the shaft provided with cutters arranged in uniformly spaced relation circumferentially and tangential to the shaft, a follower movable lengthwise of and within the opening in the work table and in screw engagement with the threaded portion of the shaft to be actuated thereby as the shaft is rotated, a guide flange secured to and projecting upwardly from one of the longitudinal edges of the work table some dis-

tance from the opening, and a guard plate secured to the same side of the work table as the flange and projecting around the edge and across the outer face of the disk in the plane of the upper surface of the work table to serve the double purpose of guarding the cutters and also for deflecting the severed materials downwardly from the cutters.

In witness whereof I have hereunto set my
10 hand this 3d day of April, 1926.

HARRY H. FISHER.
